Inventor:
William Wilburger,
By Frederick V. Wintees,
Attorney.

UNITED STATES PATENT OFFICE.

WILLIAM WILBURGER, OF BROOKLYN, NEW YORK.

LOOSE-LEAF BOOK.

Application filed December 12, 1921. Serial No. 521,781.

To all whom it may concern:

Be it known that I, WILLIAM WILBURGER, a citizen of the United States, and resident of Brooklyn, in the county of Kings and 5 State of New York, have invented certain new and useful Improvements in Loose-Leaf Books, of which the following is a full, clear, and exact specification.

This invention relates to loose leaf binders or books and has for its object to provide improved means for attaching binder posts thereto.

It is desirable to have the heads of the binder posts concealed from the outside of 15 the book, so that there will be no danger of said heads scratching the surface on which the book is laid. It is also desirable to be able to quickly attach and detach the posts and at the same time to insure against accidental separation or displacement of said 20 posts from the binder. The present invention contemplates the provision of means for accomplishing these desired results. Other objects will appear as the description 25 proceeds.

The invention will be first hereinafter described in connection with the accompanying drawings, which constitute part of this specification, and then more specifically pointed 30 out in the claims at the end of the description.

In the accompanying drawings, wherein similar reference characters are used to designate corresponding parts throughout the 35 several views:

Figure 1 is a sectional view of a loose leaf binder or book embodying the present invention, the section being taken in line with one of the binder posts which is itself shown 40 in elevation, and the top of the book being open.

Figure 2 is a fragmentary view of the inner portion of the binder showing post-holding means attached to the inner surfaces of its upper and lower portions, a post being shown with its integral lower head engaged with one of said holding means, while its detached upper head is engaged with another holding means.

Figure 3 is a sectional view similar to Figure 1 of a modified form of binder or book in which the upper ends of the binder posts project through the top of the binder.

Figure 4 is a detailed longitudinal section of one of the posts drawn to a larger scale, and

Figure 5 is a lower end view of the binder post.

Referring first to Figures 1 and 2, the back 1 of the binder has top and bottom covers 2 and 3, respectively, hinged thereto by flexible strips 4, preferably arranged between parallel heads 5, so that said covers may be folded flat upon said back as the top cover is shown in Figure 1. To the inner faces of the upper and lower portions of the back 1 metal strips 6 are fastened in any suitable manner so as to extend substantially the full width of the book. Each strip 6 has tongues 7 cut therefrom and extending parallel thereto at a suitable distance to permit the heads of the binder posts to be inserted between the tongues and strips. Each tongue is slit longitudinally to form a key-slot 8 having a round inner portion 9 and 75 outwardly diverging lateral edges 10.

The binder posts 11 are preferably made as best shown in Figure 4, each having its shank formed from a single piece of coiled wire, the upper end portion 12 being of 80 smaller diameter than the lower portion 13, to facilitate the placing of leaves 14 over said shanks. Each leaf has a hole 15 to loosely fit over the shank of each binder post. A head 16 is formed integral with the lower end 85 of the shank of each post by extending the wire in a plurality of spiral coils all lying in the same plane at right angles to the axis of the shank. The upper end of each shank is fitted with a removable head 17 which may have a pair of prongs 18 to extend into the reduced upper end portion 12. The inner ends of said prongs are preferably spread apart at 19 to yieldingly engage the spaces 90 between the coils of the wire for retaining the head in place but the prongs are sufficiently resilient to permit said spread ends 19 to be inserted into the upper end 12 of the shank without difficulty.

The binder posts are attached to the back 100 of the binder by engaging their lower ends with the key-slots 8 in the lower strip 6. In effecting this engagement the integral lower heads 16 of the binder posts are inserted between the tongues 7 and the plate 6, while 105 the lower end portions of the shanks of said posts are pushed along between the diverging edges of the key-slots 8 until they snap into engagement with the round inner ends 9 thereof it being understood that said 110 rounded ends 9 are of substantially the same diameter as said lower ends of the shanks,

and that the coiled spring wire of which said shanks are made has sufficient resiliency to permit them to pass the restricted portions of the key-slots at the junctions of said 5 diverging edges 10 and round ends 9. The heads 17 are removed from the shanks of the posts while the leaves are being placed in the binder, and are engaged with their shanks after being attached to the tongues 7 of the upper strip 6, as shown in Figure 2. Said removable heads 17 are engaged with said tongues by means of the key-slots 8 therein, as will be readily understood from the showing in Figures 1 and 2.

10 15 As shown in Figure 3, the metal strip 6 may be omitted from the upper portion of the binder and the latter provided with holes 20 through which the prongs 18 on the removable heads 17 are passed to engage 20 with the upper ends of the shanks of the binder posts. In this modified form of the invention said removable heads 17 are exposed on the outside of the upper face of the binder but this is not objectionable because 25 said heads do not come in contact with the surface on which the book is laid, unless said book is turned completely over by mistake and the exposure of said heads serve as a warning against such an occurrence.

30 I claim:

1. The combination with a loose leaf binder, of a metal strip secured to its inner surface and having an integral key-slotted tongue cut and spaced from said strip, and 35 a binder post having a shank to engage said slot substantially as described.

2. The combination with a loose leaf

binder, of a metal strip secured to its inner surface, key-slotted tongues spaced from said strip, said slots having round inner portions 40 and converging marginal portions leading to said round portions from the edges of the tongues, and binder posts to engage said slots substantially as described.

3. The combination with a loose leaf binder, of a metal strip secured to its inner surface, key-slotted tongues spaced from said strip, said slots having round inner portions and converging marginal portions leading to said round portions from the 45 edges of the tongues, the space between the inner ends of said converging portions being less than the diameter of said round portions, and binder posts having resilient shanks to engage said slots substantially as 50 described.

4. The combination with a loose leaf binder, of a metal strip secured to its inner surface, a key-slotted tongue attached to and spaced from said strip, said slot having a round inner portion and converging marginal portions leading to said round portion from the edge of the tongue, the space between the inner ends of said converging portions being less than the diameter of said 65 round portion, and a binder post having a head to fit between the tongue and strip, and a shank of substantially the same diameter as said round portion of the slot to engage the latter after being forced between the 70 inner ends of said converging portions.

In testimony whereof I have signed my name to this specification.

WILLIAM WILBURGER.
